UNITED STATES PATENT OFFICE

157,333

BADGE OR SIMILAR ARTICLE

Eunice Bonner, Gary, and Ethel Bowers, Elkhart,
Ind., assignors to Mothers of World War No. II,
Inc., Indianapolis, Ind., a corporation

Application November 17, 1948, Serial No. 149,687

Term of patent 14 years

(Cl. D29—2)

To all whom it may concern:

Be it known that we, Eunice Bonner and Ethel Bowers, citizens of the United States and residents respectively of Gary, county of Lake, and State of Indiana, and Elkhart, county of Elkhart, and State of Indiana, have invented a new, original, and ornamental Design for a Badge or Similar Article, of which the following is a specification, reference being had to the accompanying drawing, forming part thereof.

In the drawing

Fig. 1 is a front view of a badge or similar article, showing our new design.

Fig. 2 is an edge view of the article.

The essential features of our design reside in the portion shown in full lines and the shading is to show contrasting colors.

We claim:

The ornamental design for a badge or similar article, substantially as shown and described.

EUNICE BONNER.
ETHEL BOWERS.
